UNITED STATES PATENT OFFICE.

NICHOLAS GLOCK, JR., OF KENTON, OHIO.

WHIFFLETREE-HOOK.

SPECIFICATION forming part of Letters Patent No. 660,423, dated October 23, 1900.

Application filed September 7, 1900. Serial No. 29,270. (No model.)

To all whom it may concern:

Be it known that I, NICHOLAS GLOCK, Jr., a citizen of the United States, residing at Kenton, in the county of Hardin and State of Ohio, have invented certain new and useful Improvements in Whiffletree-Hooks, of which the following is a full, clear, and exact specification.

The object of this invention is to provide means whereby the trace will be prevented from accidentally slipping from the hook. This object is accomplished by the use of the device illustrated in the accompanying drawings; and the invention consists in certain novel features of the same, as will be herein-after first fully described and then particularly pointed out in the claims.

In the drawings, mention of which has just been made, Figure 1 is a side elevation of a whiffletree - hook embodying my improvements, and Fig. 2 is an enlarged detail perspective view.

The hook is attached to the end of the whiffletree by the usual eye A, and the hook proper, B, extends forward from the eye, as shown. Just beyond the eye, on the inner or upper side of the hook, I form the projection C, which presents a shoulder or stop D for a purpose presently stated, the end of the hook being brought back to a point adjacent to the said projection, so that the space between the projection and the end of the hook is just sufficient to admit the trace. Below the projection C a link E is pivoted in the body of the hook, the length of the link being greater than the distance between the projection and the end of the hook, as shown. Ordinarily one link will be sufficient to retain the trace within the hook; but I prefer to employ a second link F, pivoted in the end of the hook and slightly smaller than the link E, so as to fit within the same, as clearly shown in Fig. 1. These links may be pivoted in sockets formed in the sides of the hook without any reinforcing construction; but I deem it advantageous to provide the bosses G around the sockets, so as to give an extended bearing to the pivotal end of the link without unduly increasing the weight of the hook, and in order to facilitate the mounting of the links notches H are cut in the rear sides of the bosses. When

the links are to be applied, their ends are slipped through these notches and spring into the sockets in the hook.

The operation of the device will, it is thought, be readily understood. When the trace is engaged in the hook, it is passed between the end of the hook and the adjacent projection and forces the links against the inner surfaces of the hook. Should the trace then make any backward movement, its end will strike against the links and cause them to swing toward each other across the end of the trace. As the links exceed in length the distance between the end of the hook and the projection, the shorter link will strike against the shoulder D, and thereby effectually block and arrest the movement of the trace, so that it cannot possibly become accidentally released. The free ends of the links may be weighted, if desired, to maintain them in position across the end of the trace. Inasmuch as the end of the link strikes against and rests on the shoulder D, the trace cannot push it beyond said shoulder and thereby escape from the hook. In order to release the trace, it is necessary to manually hold the links out of the path of the trace and then disengage it from the hook while the links are so held.

Having thus described my invention, what I claim, and desire to secure by Letters Patent, is—

1. The combination with a whiffletree-hook having sockets in its sides and provided with bosses around said sockets having notches in their rear edges, of links having their ends passed through said notches and sprung into the sockets.

2. The combination with a whiffletree-hook having sockets in its sides at or near its end and at a point opposite its end, of links pivoted in said sockets, both said links being greater in length than the opening of the hook.

In testimony whereof I have signed this specification in the presence of two attesting witnesses.

NICHOLAS GLOCK, JR.
